DESIGN FOR A CASING FOR INDICATORS SUCH AS THERMOMETERS, BAROMETERS, CLOCKS, AND THE LIKE

Charles E. Steiner, Detroit, Mich.

Application April 14, 1934, Serial No. 51,416

Term of patent 7 years

To all whom it may concern:

Be it known that I, CHARLES E. STEINER, a citizen of the United States residing at Detroit, in the county of Wayne and State of Michigan, have invented a new, original, and ornamental Design for a Casing for Indicators such as Thermometers, Barometers, Clocks, and the like, of which the following is a specification, reference being had to the accompanying drawing, forming part thereof, in which

Fig. 1 is a front elevational view of a casing for indicators such as thermometers, barometers, clocks, and the like, showing my new design.

Fig. 2 is a side elevational view of the same.
I claim:

The ornamental design for a casing for indicators such as thermometers, barometers, clocks, and the like, as shown.

CHARLES E. STEINER.
